UNITED STATES PATENT OFFICE

139,870

DESIGN FOR A TABLE

William H. McDonald, Bloomington, Ind., assignor to The Nurre Companies, Inc., Bloomington, Ind., a corporation of Indiana

Application March 10, 1944, Serial No. 112,853

Term of patent 3½ years

(Cl. D33—14)

To all whom it may concern:

Be it known that I, William H. McDonald, a citizen of the United States and a resident of Bloomington, in the county of Monroe and State of Indiana, have invented a new, original, and ornamental Design for a Table, of which the following is a specification, reference being had to the accompanying drawing, forming a part thereof, wherein:

I claim:

The ornamental design for a table, as shown.

WILLIAM H. McDONALD.
